UNITED STATES PATENT OFFICE.

CLAS J. JULSTEDT, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

SELF-COCKING FIRING MECHANISM.

Application filed July 26, 1922. Serial No. 577,677.

To all whom it may concern:

Be it known that I, CLAS J. JULSTEDT, a citizen of the United States, and residing at Bethlehem, Lehigh County, State of Pennsylvania, have invented certain new and useful Improvements in Self-Cocking Firing Mechanisms, of which the following is a specification.

This invention relates to breech loading guns and particularly to firing mechanisms for guns of the sliding breech block type.

One object of this invention is to provide a firing mechanism in the form of a self-contained unit which is readily removable from the breech block, and readily replaceable in order to facilitate inspection, and repair. Another object is to provide a firing mechanism in which the resistance to the pull exerted on the firing lever is greatest at an intermediate point in the travel of the lever and decreases toward the end of its movement, so that only a slight pull on the lever is required at the instant of firing.

One form of the invention is illustrated in the accompanying drawings in which:

Fig. 1 is a vertical section through the breech end of a gun with the parts of the firing mechanism, in their normal or at rest position;

Fig. 2 is a similar view showing the positions which the parts of the mechanism occupy at the instant the hammer is released to strike the cartridge;

Fig. 3 illustrates the position which the parts of the mechanism occupy an instant after the firing pin has struck the primer;

Fig. 4 is a section on the line 4—4 of Figure 1;

Fig. 5 is a rear elevation of the firing mechanism holder or frame removed from the breech block;

Fig. 6 is a plan view of the same;

Fig. 7 is a diagram showing the force required in pulling the firing lever at each point in its angular travel;

Fig. 8 is a diagram showing the compression of the main spring in pounds for the various positions which it occupies in the firing operation;

Fig. 9 is a fragment of a section on the line 9—9 of Figure 4 showing the means for retracting the hammer in its normal or at rest position;

Fig. 10 is a similar section taken on the line 10—10 of Figure 11 showing said means in the fired position; and

Fig. 11 is a section on the line 11 of Figure 10.

The breech portion 10 of the gun has a breech recess 12 in which the breech block 13 is slidably retained, and is cut away axially of the bore at 14 to allow the introduction of a projectile with its powder case and the ejection of the case after firing, in well known manner. The breech block is 65 also cut away at 16 for this purpose, the apertures 14 and 16 being in register when the breech block is lowered. Any usual extractor (not shown) may be used and any well known means for raising and lowering 70 the block (or moving it to one side in the case of a horizontally movable block).

The breech block has a central transverse recess or bore 17 extending from the back of the block toward its front face, the bore 75 being sufficiently large to receive the hammer and tapering at its forward end to a small firing pin opening 26 in the face of the block. The block also has a recess 18 extending upwardly from the bottom of the 80 block and intersecting the central bore 17. The recesses formed in the block do not, however, so weaken it that it does not solidly support the shell case 15 during firing.

A holder for supporting the firing mechanism is shown in Figures 5 and 6, this holder comprising a casing 19 and side cover 20, the whole forming a box or frame, open at the ends, in which the firing mechanism is mounted. The casing 19 fits closely in the 90 recess 18 in the breech block and for the purpose of removably securing it therein is provided with a flat leaf spring, secured to the end of which is a button 22 adapted to fit snugly within the rear end of the bore 17. 95 The button and spring constitute a spring latch.

A hammer 23 is pivoted at 24 in the casing 19 and carries at its free end a firing pin 25 which is adapted to protrude through 100 the hole 26 to strike the primer in the cartridge case. A lever or operating arm 27 for the mechanism is pivoted in the frame at 28 and is provided with a recess to accommodate a sear 30 which is pivoted at 105 29 in such recess. The pivot pin 28 passes

through the recess in the lever and forms a stop for the shoulders 31 of the sear for the purpose of limiting the motion of the sear relative to the firing lever, so that the sear 5 will rock with the lever when the latter is pulled.

To the other end of the sear is pivoted one end of a telescoping rod 32, the opposite end of which carries a trunnion 33 fitting in a 10 recess 34 in the hammer. At each end of the rod is a shoulder 36, and between these shoulders the firing spring 37 is confined, the rod acting as a guide to keep the coiled spring from buckling on being compressed. The 15 sear has a nose 38 which bears against a shoulder 39 when the lever is pulled to rotate the hammer about its pivotal axis. The movement of the lever in a rearward direction is limited by a stop 19' on the frame 20 which engage a shoulder 40 on the lever.

For locking the lever against accidental operation and for assisting in partially cocking the hammer to enable the operator to remove the firing mechanism from the breech block, a safety locking lever 42 is provided. This lever is pivoted to the frame and when swung into the position shown in Figure 1, its nose 43 lies in the path of the shoulder 41 on the firing lever so that the 25 latter cannot be moved. The lock is held in either safe or firing position by the point of a spring pressed plunger 44 engaging either depression 45 in the frame.

In a recess in the hammer near the pivot is 30 disposed a plunger 46 which is constantly urged outward by a spring 47, but is prevented from being forced completely out of said recess by a pin 46^a pocketed in a recess 46^b bored to intersect at right angles the 35 aforementioned recess containing the plunger 46 and in the same axial plane. The face of the plunger is hollowed out at 48 to conform with the contour of the pin 46^a 40 with which it engages. The diameter of the pin 46^a is less than the diameter of its recess to allow the necessary longitudinal movement of the plunger. The open end of the recess containing the pin 46^a is closed by the 45 inner face of the casing 19. Fixed in the casing is a stop 49 which engages the pin 46^a when the hammer is in its normal and fired 50 positions.

The normal position of the mechanism is 55 as shown in Figure 1. To operate the device, the safety catch is first set to "fire" position as in Figure 2. The lever is then pulled through about 60° during which the following successive movements take place. The spring 37 being slightly compressed in the "at rest" position of Figure 1, exerts 60 initially a small force on the sear, as indicated in Figure 8. Inasmuch as the shoulder 31 engages the pivot pin 28 the sear is rotated with the lever, the spring being further compressed, but only a slight pull being

required (as shown graphically in Figure 7) until the nose of the sear engages the shoulder 39. From this point on the hammer is rotated to the cocked position, and the spring 70 compressed in this movement nearly to its solid height, indicated by "height cocked" in Figure 8.

It will be noted that throughout the pull thus far, the direction of the force exerted by the spring on the lever through the intermediary of the sear is to the left of the pivot 28. At maximum compression the line of force passes through the pivot 28. Stop 19' engages the shoulder 40 to prevent further movement of the lever as soon as the line of force falls slightly to the right of the pivot 28. The spring now exerts a force on the sear tending to rotate it in a clockwise direction, and to thereby force the firing lever against the stop. Before the lever reaches the stop the arc described by the sear nose falls outside that described by the shoulder 39, the sear releases the hammer, and the spring forces the hammer sharply forward, the firing pin being projected through opening 26 in the front of the breech block to strike the primer, the spring 47 being compressed by the fast moving hammer. Referring to Figures 3 and 8 it is seen that the line of action of the spring is now to the left of the pivot 28, and that the spring is still somewhat compressed. Hence, a force is exerted on the firing lever through the intermediary of the sear 30 which moves the lever to the right, resetting the mechanism to the position shown in Figure 1. During this resetting movement the sear rocks on its pivot 29 and the nose 38 rides past the shoulder 39.

When the lever has been returned to the extreme right or simultaneously with this movement, the spring 47 overcomes spring 37 so that the firing pin is retracted slightly and will not project to foul the cartridge case when the breech block is lowered.

It has been noted that the line of thrust of the spring approaches the pivot 28 as the spring nears its maximum compression, and passes through the pivot when the spring is fully compressed. The parts are so designed that the maximum resistance to pull on the firing lever occurs materially before the maximum compression of the spring, and as shown graphically in Figure 7, is greatest when the firing lever has completed about half its total angular movement. From this point on, the pulling force required decreases rapidly and is zero at the instant of firing. This is a material advantage, since a quick jerk on the lanyard develops sufficient momentum to complete the operation of firing, whereas in the usual construction heretofore used, the maximum trigger pull occurs simultaneously with maximum spring compression and substan- 125 130 135 140 145 150 155 160 165 170 175 180

tially at the instant of firing, thus requiring a continually increasing pull on the firing lever.

When it is desired to remove the firing mechanism from the breech block, the firing lever is pulled until the shoulder 41 has passed the stop 19'. The locking lever 42 is then swung to the position of Figure 1 and the trigger pulled until shoulder 40 engages the projection 43. At this point the hammer is almost fully cocked, yet there is sufficient clearance between the hammer and the spring 21 to allow the button 22 to be pressed forward releasing the firing mechanism assembly to be withdrawn from the recess 18. Upon inserting the mechanism into the recess, the button 22 automatically snaps into position and locks the casing 19 in place.

To one skilled in the art the advantages of the invention will be apparent and it will be obvious that changes may be made in the design and arrangement of the elements of the mechanism to adapt the same for use with guns of various types, without departing from the scope and spirit of the invention.

Having thus described the invention what is claimed as new and desired to be secured by Letters Patent is:

1. The combination with a breech block of the sliding type having a recess extending thereinto from one face, and a second recess extending thereinto from another face and opening into the first recess, of a frame, having a firing mechanism mounted thereon, insertable into and removable from one of said recesses, said frame having also means to cooperate with the breech block to lock the frame in operative position within the block, said locking means being accessible through the other of said recesses.

2. The combination with a breech block of the sliding type having a recess extending thereinto from one face and a second recess extending thereinto from another face and opening into the first recess, of a frame, having a firing mechanism mounted thereon, insertable into and removable from one of said recesses, said frame having a spring latch to cooperate with the breech block in securing the frame in operative position within the block, said spring latch being accessible for manual operation through the other of said recesses.

3. In a breech loading gun, in combination, a breech block having a transverse bore, and an intersecting longitudinal recess, a frame containing a complete firing mechanism inserted in the longitudinal recess, and a spring latch on the frame engaging the wall of the transverse bore to hold the frame in place.

4. In a firing mechanism for guns, in com-

bination, a firing hammer, a firing spring, and means for stressing the spring to operate the hammer, said means including an operating element, the spring and operating element being so mounted as to change their relative positions during the stressing operation, the resisting pressure of the spring on the operating element decreasing as the stress in the spring increases.

5. In a firing mechanism for guns, in combination, a firing hammer, a coiled firing spring, and means for stressing the spring to operate the hammer, said means including an operating element for axially compressing the spring, the spring and operating element being so mounted as to change their relative positions during the stressing operations, the resisting pressure of the spring on the operating element decreasing as the stress in the spring increases.

6. In a firing mechanism for guns, in combination, a firing hammer, a coiled firing spring, and means for stressing the spring to operate the hammer, said means including a pivoted operating element for axially compressing the spring, the spring and operating element being so mounted as to change their relative positions during the stressing operation, the axis of the spring moving toward the axis of rotation of the pivoted operating element as the spring is stressed, the resisting pressure of the spring on the operating element decreasing as the stress in the spring increases.

7. In a firing mechanism for guns in combination, a hammer, a spring for operating the hammer, a pivoted operating element for cocking the hammer and stressing the spring, the operating element being adapted while stressing the spring to shift the line of action of the spring toward the pivot.

8. In a firing mechanism for guns in combination, a hammer, a spring for operating the hammer, a pivoted operating element for cocking the hammer and stressing the spring, the operating element being adapted while stressing the spring to shift the line of action of the spring from one side of the pivot to the other side thereof.

9. In a firing mechanism for guns in combination, a pivoted hammer, a pivoted operating element and a spring interposed between the operating element and the hammer, the operating element being adapted to rotate the hammer against the action of the spring and subsequently to release the hammer for operation by the spring.

10. In a firing mechanism for guns in combination, a pivoted hammer, a pivoted operating element, and a firing spring interposed between the operating element and the hammer, the operating element being adapted to rotate the hammer against the action of the spring and subsequently to release the hammer to be driven forward.

- by the firing spring, a stationary abutment and a spring disposed in the hammer and cooperating with the abutment to retract the hammer slightly after firing against the 5 action of the firing spring.
11. In a firing mechanism for guns in combination, a pivoted hammer, a firing spring, and a retracting spring, positioned to act on the hammer adjacent the pivotal 10 axis thereof, the firing spring being adapted to actuate the hammer to firing position and the retracting spring being adapted to retract the hammer after firing against the action of the firing spring.
12. In a firing mechanism for guns in combination, a pivoted hammer, means for actuating the hammer to firing position, a stationary abutment, elastic means interposed between the hammer and the abutment, the abutment being adapted to stress the elastic means when the hammer is actuated to firing position, and the elastic means being adapted to retract the hammer from firing position.
13. In a firing mechanism for guns in combination, a hammer, a firing spring and means for cocking the hammer against the action of the spring, for shifting the line of action of the spring whereby the hammer is released, the spring being adapted when the hammer is released to force the hammer forward and to change its line of action to reset the operating means.
14. In a firing mechanism for guns, in combination, a hammer, a pivoted firing lever, a firing spring, means on the firing lever adapted when the lever is actuated to cock the hammer against the spring, to cause the spring to exert a force on the lever in the direction of its actuation and to release the hammer, and means for preventing movement of the firing lever under the action of said force, the spring being adapted after the release of the hammer to change the direction of its force on the firing lever to reset the latter.
15. In a firing mechanism for guns in combination, a hammer, a pivoted firing lever having two shoulders thereon, a firing 50 spring interposed between the lever and the hammer, means on the lever adapted when the lever is actuated to cock the hammer against the action of the spring, cause the spring to exert a force on the lever in the direction of its actuation and to release the hammer and a safety lock adapted to cooperate with either of said shoulders to prevent initial movement of the trigger, or to prevent release of the hammer.
16. In a firing mechanism for guns in combination, a pivoted hammer having a recess therein and adapted to be actuated to firing position, and means for retracting the ham- 55 60 65 70 75 80 85 90 95 100 105 110 115 120
- mer from firing position comprising a stationary abutment, a member in the recess adapted to contact with the abutment, and elastic means interposed between said member and the hammer, the abutment being adapted to stress the elastic means when the hammer is actuated to firing position.
17. In a firing mechanism for guns in combination, a hammer adapted to be actuated to firing position and having a pair of mutually transverse recesses therein, and means for retracting the hammer from firing position comprising a plunger in one of said recesses, a spring adapted to urge the plunger outward, a pin in the other recess adapted to retain the plunger and to permit limited movement thereof, and a stop adapted to engage the pin to compress the spring when the hammer is fired.
18. In a firing mechanism for guns in combination, a hammer having a shoulder, a fulcrumed firing lever, a sear pivoted on the firing lever, a spring interposed between the hammer and the sear, and a toe extending from the sear and adapted to engage said shoulder when the firing lever is rotated.
19. In a firing mechanism for guns in combination, a hammer having a shoulder, a fulcrumed firing lever, a sear pivoted on the firing lever, a spring interposed between the hammer and the sear, an abutment member which limits the pivotal movement of the sear, and a toe extending from the sear and adapted to engage said shoulder when the firing lever is rotated.
20. In a firing mechanism for guns in combination, a hammer having a shoulder, a fulcrumed firing lever, a sear pivoted on the firing lever, a spring interposed between the hammer and the sear, an abutment member normally engaging the sear to prevent the pivoted movement thereof, and a toe extending from the sear and adapted to engage said shoulder when the firing lever is rotated.
21. In a firing mechanism for guns in combination, a hammer having a shoulder, a fulcrumed firing lever, a sear pivoted on the firing lever, a spring interposed between the hammer and the sear and adapted to be compressed by the rotation of the firing lever, an abutment member normally engaging the sear to prevent the pivotal movement thereof, and a toe extending from the sear and adapted to engage said shoulder when the firing lever is rotated to compress the spring and to disengage said shoulder when the maximum compression of the spring is reached.
- In testimony whereof I hereunto affix my signature.
- CLAS J. JULSTEDT.
